UNITED STATES PATENT OFFICE.

ERNEST D. ANDERSON, OF NEW YORK, N. Y., ASSIGNOR TO E. D. ANDERSON INC., OF NEW YORK, N. Y., A CORPORATION OF NEW YORK.

WRAPPING-MACHINE.

1,336,549.

Specification of Letters Patent. Patented Apr. 13, 1920.

Application filed June 12, 1917. Serial No. 174,191.

To all whom it may concern:

Be it known that I, ERNEST D. ANDERSON, a citizen of the United States, and resident of New York city, borough of Manhattan, in the county of New York and State of New York, have invented certain new and useful Improvements in Wrapping-Machines, of which the following is a specification.

10 My invention has reference to improvements in machines for wrapping articles or packages of goods and has for its object to provide simple and effective means to supply articles and wrappers therefor successively, 15 to apply the articles to the wrappers, and to close the wrappers around the articles and deliver the wrapped packages.

In carrying out my invention I provide means, such as a magazine, to contain the 20 articles or packages to be wrapped, means to supply wrappers for the articles, means to successively feed the wrappers and the articles into juxtaposition and temporarily retain the articles opposing the wrappers, 25 means to push the articles with the wrappers into a passage or channel wherein the wrappers are partially folded around the articles, means to close or fold projecting portions of the wrappers upon the articles, 30 and means to discharge the wrapped articles or packages.

In the embodiment of my invention illustrated in the accompanying drawings the arrangement is such that the wrappers are 35 successively fed to a receiver to temporarily retain the wrappers in a position substantially on edge, and the articles are successively fed to a retainer in position between such retained wrappers and a plunger, 40 where the articles are temporarily retained in position to permit the plunger to advance and push the articles against the wrappers successively, and thence to push the assembled wrappers and the articles together into 45 the aforesaid passage or channel for causing preliminary folding of the wrappers over the edges of the articles, the wrappers and articles being successively pushed by the plunger into a position for the operation, 50 upon projecting portions of the wrappers, of folding devices to complete the folding or closing of the wrappers upon the articles, and for discharge of the wrapped articles or packages from the machine.

55 My invention comprises novel details of

improvement and combinations of parts that will be more fully hereinafter set forth and then pointed out in the claims.

Reference is to be had to the accompanying drawings forming part hereof, wherein,

Figure 1 is a front elevation of a wrapping machine embodying my invention, the plunger being illustrated at the commencement of its working stroke; Fig. 2 is an enlarged section substantially on the line 2, 2, 65 in Fig. 5; Fig. 3 is a cross section substantially on the line 3, 3, in Fig. 1; Fig. 4 is a sectional view through the magazine and feeding devices for the articles to be wrapped; Fig. 5 is a plan view of the machine; Fig. 6 is a perspective view of an article adapted to be wrapped in accordance with my invention; Fig. 7 is an enlarged sectional view substantially on the line 7, 7, 70 in Fig. 1; Fig. 8 is a section substantially 75 on the plane of the line 8, 8, in Fig. 7, and also substantially on the plane of the line 2, 2, in Fig. 5; Fig. 9 is a view similar to Fig. 8, illustrating parts in different positions; Fig. 10 is a face view of the delivering end of the chute for the articles, looking from the left on the plane of the line 19, 19, in Fig. 8; Fig. 11 is a detail of part of Fig. 10; Fig. 12 is an end view of the machine, 80 partly in section, looking from the lefthand side of Fig. 1; Fig. 13 is a cross section on the line 13, 13, in Fig. 1; Fig. 13^a is a cross section through wrapper folders 57, 58, in an operated position; Fig. 14 is a section on the line 14, 14, in Fig. 13; Fig. 15 is a perspective view of a wrapped package; Fig. 16 is a partly sectional rear view of the machine looking from the side opposite to that shown in Fig. 1; Fig. 17 is a sectional view through the chute for the articles near 95 the lower end thereof, the section being taken substantially on the line 17, 17, in Fig. 7; Fig. 18 is an enlarged sectional plan view, substantially on the line 18, 18, in Fig. 19, illustrating stationary folding devices 100 for wrappers; Fig. 19 is a vertical section, substantially on the line 19, 19, in Fig. 18, parts being omitted; Fig. 20 is a sectional view similar to a portion of Fig. 18, illustrating a preliminary step in folding the 105 wrapper upon an article 4, as the article and wrapper are pushed into the stationary folders; Fig. 21 is a cross section on the line 21, 21, in Fig. 20, diagrammatically illustrating a primary wrapper folding 110

step; Fig. 22 is a perspective view diagrammatically illustrating the wrapper in a primary partly folded stage; Fig. 23 is a sectional view substantially corresponding to Fig. 21, but taken on the line 23, 23, of Fig. 19; Fig. 24 is a perspective view illustrating a partly folded wrapper as would appear after passing the folders 103, 104; Figs. 25 and 26 are respectively perspective and face views illustrating operations of the folders 59, 60; Fig. 27 is a detail view illustrating the appearance of the wrapper after said folders have been withdrawn therefrom; Figs. 28 and 29 are perspective views diagrammatically illustrating operations of folders 57, 58, and Fig. 30 is a detail view illustrating one of the retaining stops for the wrappers of magazine 40.

20 My improved machine may comprise any suitable frame for supporting the operating parts hereinafter referred to. I have shown such frame comprising a standard or upright 1, provided with a table top or plate 2. At 3 is a magazine or receptacle for articles or goods 4, which are shown stacked in said magazine and adapted to be fed or delivered successively therefrom. I have shown the stack of articles resting upon the bottom 5 of the magazine, which bottom is shown extending to a downwardly disposed chute 6, the articles 4 being adapted to slide over the curved part 5^a to enter the chute. The lower end of the chute is secured upon table 2, and the upper end may support the magazine. Upon the bottom plate 5 that is extended to one side of the magazine is a reciprocative pusher plate or bar 7 operative in guides 8 on said bottom (Figs. 1, 4, 5 and 16). Said pusher is shown provided with a downward projection 7^a passing through a slot 5^b in bottom plate 5, and connected to a link or bar 9 shown pivotally connected with a lever or rock arm 10 which is shown pivotally supported at 11 upon the chute (Fig. 1). When lever 10 is rocked the pusher 7 will be reciprocated to discharge or feed the articles 4 successively from the bottom of the stack to chute 6. The lower end of chute 6 is shown provided with a terminal stop 6^a for the articles 4, (Figs. 7 and 17), providing a retainer for said article, and the opposite side walls of the chute are open or cut away at 6^b, 6^c (Figs. 7, 8 and 9). At 12 is a plunger guided to pass through said openings 6^b, 6^c of the chute to push articles 4 therefrom. Said plunger is shown carried by a rod 13 suitably guided to reciprocate in a bearing 14 carried by the main frame (Figs. 1 and 16). A crank arm 15 is shown pivotally connected with a link 16 which in turn is pivotally connected at 17 with rod 13, which crank arm is supported by a shaft 18 carried by a bracket or standard 19 on the main frame. A crank arm 20 secured to said shaft is pivotally connected at 21 with a rod 22 shown having a forked or slotted end guided upon a shaft 23 (Fig. 16). The shaft 23 is journaled in suitable bearings 23^a upon the main frame, and is shown provided with a gear wheel 25 in mesh with a gear wheel 26 upon a drive shaft 27 that is journaled in bearings 28 upon the main frame. A cam 24 is adapted to coöperate with projection 22^a on rod 22, 75 for reciprocating said rod (Fig. 16). Cam 24 may be cut in the face of the gear wheel 25 in the form of a cam-groove, or may be formed separately from said wheel to be driven by shaft 23. Shaft 27 may be rotated by any suitable means, as by a pulley 29 receiving a belt from a power source, clutch means at 30 being adapted to be operated for starting and stopping said shaft. When shaft 27 is rotated the plunger 12, 80 through the means described, will be reciprocated to push articles 4 from the retainer at the lower end of the chute. Since the plunger 12 passes transversely through said retainer to discharge goods or articles therefrom, and since the latter are fed successively to the chute, and may remain one against another therein as in Fig. 5, the plunger 12 is provided with a rearwardly extending guard 31 (Figs. 1, 7 and 16) to hold 85 back articles in the chute while the plunger operates. When the plunger is withdrawn from the retainer at the lower end of the chute a succeeding article 4 may advance into position opposite the plunger, and so on 90 successively, (Figs. 7 and 8).

At the goods delivery side of the chute is located a wrapper receiver, shown in the form of a compartment 32 having a closed bottom 32^a and spaced walls 32^b provided with opposing openings 32^c, 32^d, which are in register with the delivery opening 6^c of the chute 6 (Figs. 1, 8 and 9). Wrappers 33 are adapted to be fed successively into wrapper receiver 32 to rest on edge in position opposite the article 4 at the delivery end of chute 6, to be pushed therefrom through the opening 32^c (Figs. 8 and 9). To guide the goods into the wrapper receiver 32 against the successive wrappers 33 therein, I provide movable guides 34 which are shown pivotally supported by rods 35 (Figs. 7 to 10). The guides 34 may be secured to said rods and the latter may be journaled in brackets or the like 36 (secured upon the chute), whereby said guides may swing into the opening 6^c at the delivery side of the chute (Fig. 8) and may swing outwardly into the wrapper receiver 32 through its opening 32^c (Fig. 9) to guide 110 the articles 4 therethrough. Springs at 37 coöoperating with rods 35 and with the adjacent brackets 36 serve to operate guides 34 to close them into openings 6^c of the retainer at the end of the chute, stops 38 on said rods 115 120 125 130

being adapted to engage projections or stops 39 upon the chute to retain the guides 34 in the closed position (Fig. 8) and to permit the guides to swing outwardly. It will be noted that the wrapper receiver 32 is located on one side of the retainer at the delivery end of chute 6 so that when plunger 12 advances it will push article 4 against the guides 34, thereby causing the latter to tilt, whereby said article may be pushed against the wrapper to push the latter through opening 32^a of receiver 32 successively, such actions occurring each time plunger 12 advances. While the plunger is advanced beyond the chute 6 the guard 31 will bear on the guides 34 to permit withdrawal of the plunger from the chute, since the guard 31 is at least as wide as the plunger.

While the wrappers may be delivered into receiver 32 in any suitable manner, I have illustrated means for automatically and successively feeding the wrappers to such receiver. For such purpose a wrapper magazine or guide is indicated at 40 supported by an upright 41 on the main frame, said magazine having an opening 42 at the delivery end for the passage of the wrappers (Figs. 1 and 2). Magazine 40 is shown inclined downwardly with its delivery opening 42 over wrapper receiver 32, the latter being shown provided with a lip or guide 43 to guide the wrappers into the receiver. At 44 is a pusher for the wrappers, located within magazine 40 and shown provided with a wheel or roller 45 to roll upon the bottom of the magazine, and having a rod 46 guided by a guide 47 carried by the magazine (Figs. 1, 2 and 5). The wrappers 33 are stacked on edge in the magazine 40 and are pressed toward the delivery opening 42 by the pusher 44. Means are provided to intermittently feed wrappers from magazine 40 to receiver 32. For such purpose I have shown a rotative roller or feeder 48 secured upon shaft 23 and having a portion of its periphery reduced or cut away at 48^a, so that only the portion 48^b having the greater diameter will engage the lowermost wrapper of the stack (Fig. 2). At 40^a is a stop located at a lower corner at the delivery opening of magazine 40 (Fig. 30), adapted to resist discharge of the wrappers 33. There may be a stop 40^a at both such corners. The arrangement is such that each time roller 48 is rotated, its projecting portion 48^b will engage the lowermost wrapper and feed it from the magazine, and the lower corner or corners of such wrapper will be caused to pass the stop or stops 40^a by bending thereover, substantially as indicated in Fig. 30, the remaining wrapper or wrappers in the magazine being retained by said stop or stops from spontaneously falling out of the magazine. The wrapper thus removed from magazine 40 by roller 48, will

pass into the wrapper receiver 32, and when the reduced portion 48^a of the roller opposes the next wrapper the latter will not be fed until the projecting portion 48^b next engages said wrapper to feed it, and so on, whereby the wrappers are fed intermittently from magazine 40.

Goods or articles 4 are also fed intermittently to chute 6 in correspondence with the intermittent feeding of the wrappers. For such purpose I have shown a rod 49 slideable in guides 50 on the main frame and shown operatively connected with rod 13 by a bar 51, which rod 49 is shown provided with a projection 52 adapted to engage lever 10 so when plunger 12 moves to push an article 4 from the chute, to then cause pusher 7 to push an article from magazine 3, said pusher retaining the upper articles of the stack when thereunder. Rod 49 is also provided with a projection 53, shown extending from an upright 54 on said rod, the projection 53 being in position to engage lever 10 to cause it to rock to return from under the stack of articles on the return stroke of plunger 12 ready to push another article from the magazine.

Opposing the delivery opening 32^a of wrapper receiver 32, is a passage or channel 55 to receive the wrappers and articles from said receiver to cause partial folding of the wrappers on the articles. The passage or channel 55 is suitably secured upon frame 1 by the post 56 (Fig. 12). When plunger 12 advances it will push an article 4 from the retainer of chute 6 into wrapper receiver 32 against the wrapper therein, and will continue on thereby pushing said article against the wrapper and causing the wrapper with the article to enter passage 55 for first partially folding the wrapper over the edges of the article. Adjacent to the receiving end of passage 55 are located opposing primary wrapper folders 102 (Figs. 18, 19, 20), so spaced as to permit the article 4 and portions of the wrapper to pass therebetween. Folders 102 are narrower than the depth or width of passage 55 providing spaces on opposite sides of the folders. Said folders 102 will engage the projecting end portions 33^c of the wrapper, as the latter is pushed with the article 4 between such folders, whereby the latter will cause the wrapper to be folded at its meeting end portions against the corresponding ends of article 4, leaving projecting flaps 33^d, 33^e which will respectively pass in the aforesaid spaces along the upper and lower edges of folders 102 as the plunger continues to move forwardly (see Figs. 20 and 21). Behind the folders 102 are other folders 103, 104 within passage 55, spaced apart to permit the passage therebetween of the article 4 and wrapper thereon, the folders 103, 104 being shown rounded and

having angularly disposed V-like recesses *a* (Fig. 19), the upper and lower rounded edges of which are adapted to respectively engage the projecting flaps 33^a, 33^b at the 5 ends of the wrapper to cause the same to be turned against the previously turned in portions of the wrapper, substantially as indicated in Fig. 24, when the wrapper has reached the position substantially corresponding to the line 24, 24 in Fig. 19. At 10 such position the wrapper may be considered to be partially wrapped around article 4. In Fig. 21 the position of the wrapper within passage 55 is represented while 15 the wrapper is passing the folders 102, and the position of the wrapper is indicated in Fig. 23 where the wrapper flaps 33^a, 33^b are about to engage the folders 103, 104. Behind the folders 103, 104 the passage 55 20 has a reduced portion 55^a (Figs. 18 and 19), which is provided between the spaced walls 55^b (Fig. 18), adapted to receive the partially folded package (Fig. 24) as it is pushed by the plunger beyond or behind 25 folders 103, 104, to retain the folds of the wrapper so far completed. When the plunger is stopped at the limit of its forward operating stroke and then recedes it will leave the partially wrapped article 4 with 30 portions of the wrapper 33 extending behind the article, substantially as shown in Fig. 24. Said extended portions of the wrapper will then be in position to be folded by pairs of wrapper folders 57, 58 35 and 59, 60. The folders 57, 58 are shown opposing and vertically disposed, and the folders 59, 60 are shown opposing and horizontally disposed (at right angles to the folders 57, 58), said folders being adapted 40 to engage respectively the projecting portions 33^a, 33^b, 33^c, 33^d of wrapper 33. The folders 57, 58 are adapted to reciprocate in vertical guides 61 carried by passage 55, and the folders 59, 60 are adapted 45 to reciprocate in transverse guides 62 carried by passage 55, whereby said folders may be guided to reciprocate adjacent to the rearward side of article 4 within passage 55 to fold the respective projecting 50 portions of the wrapper against the article. By preference, the pair of folders 57, 58 are so guided as to travel in parallel planes, such as to overlap against folded portions of the wrapper, as illustrated in 55 Fig. 13^a. Means are provided to reciprocate the said folders in timed relation to the operation of plunger 12. I have shown projections 63, 64 operative in openings 65, 66 respectively in the folders 57, 58 (Figs. 60 1, 5 and 13), which projections extend from shafts 67, 68 suitably journaled in brackets 69, 70 supported by the main frame. Said shafts are shown provided with crank arms 71, 72 respectively, which extend toward the 65 projection 53. Said shafts are shown pro-

vided with springs 73, 74 tending normally to move the crank arms 71, 72 toward reciprocal projection 53. Said crank arms are shown provided with rollers 75, 76 to bear on projection 53 (Fig. 1). 70 Projection 53 is shown provided with dogs 77, 78 pivotally supported on said projection to encounter the rollers 75, 76 to cause the respective crank arms 71, 72 to spread apart during a forward stroke of plunger 75 12, to cause the folders 57, 58 to approach 12, to fold the respective parts 33^a, 33^b of the wrapper over the rearward side of an article previously deposited in passage 55. Said dogs 77, 78 will pass beyond the rollers 75, 80 76, during forward travel of plunger 12, whereby the springs 73, 74 may cause shafts 67, 68 to be rocked reversely for separating the folders 57, 58 from the wrapper, before a succeeding wrapper and an article 85 therein is brought to the wrapper folding position. Springs 79, 80 secured on projection 53 co-operate respectively with dogs 77, 78 to retain the latter in normal position and to permit said dogs to slide over the 90 corresponding rollers 75, 76 on the return stroke of projection 53. It will be noted that dog 77 is located in advance of dog 78 on the forward stroke of the plunger, whereby arm 71 will be rocked to cause folder 57 95 first to advance to fold the corresponding part 33^a of the wrapper against the article, and the dog 78 next will cause operation of arm 72 to cause folder 58 to advance to fold the portion 33^b of the wrapper against the 100 article, and then continued movement of said dogs will cause them to pass beyond the arms 71, 72 whereupon spring 73, 74 will restore said arms to normal, thereby also causing the folders 57, 58 to move outwardly or spread apart. Since dog 77 is located in advance of dog 78 the dog 77 will release arm 71 to permit return from the 105 wrapper of folder 57 sufficiently before the advance of folder 58, caused by the operation of dog 78 on arm 72, so that folder 57 will not interfere with the folding of the part 33^b of the wrapper over the previously folded part 33^a thereof. The dogs 77, 78 will snap back into position opposing the 110 rollers 75, 76 when released from the latter on the return stroke of projection 53. The folders 59, 60 will be reciprocated to fold the end portions 33^c, 33^d of the wrapper over the rear side of article 4 during a return 115 stroke of the plunger 12 after it has deposited a wrapper and article in passage 55, and during the next forward stroke of the plunger, the folders 57, 58 will fold the portions 33^a, 33^b of said wrapper over the 120 aforesaid folded portions 33^c, 33^d thereof, while a succeeding article and wrapper are being pushed to wrapper folding position (Fig. 4). For such purpose I have shown the folders 59, 60 provided with projections 125 65

81, 82 respectively (Figs. 1, 5, 12, 13, 14) which projections are suitably guided as at 83 to reciprocate. Means are provided to reciprocate the guides 59, 60 in timed relation to the operation of the guides 57, 58. For such purpose I have shown rock arms 84, 85 carried by shafts 86, 87 journaled in bearings 88 supported by the main frame, the free ends of arms 84, 85 being movably connected with the projections 81, 82 as by pin and slot connection 89 (Fig. 5). Shafts 86, 87 are shown provided with crank arms 90, 91 that are shown extending toward each other and pivotally connected together by a pin 92 operating in slots 93 in said arms, whereby said arms may rock together, (Fig. 5). A rock arm 94 is connected with said pin 92 and is pivotally carried by a shaft 95 journaled in a bearing 96 carried by the main frame. Said shaft 95 is provided with a crank arm or projection 97, shown extending substantially oppositely from the direction of arm 94 and connected with spring 98, the opposite end of which is shown connected with a projection 99 on a delivery guideway 100. A projection 101 is shown carried by the upright 54 and adapted to engage and to operate the arm 97 to cause operation of arm 94, whereby pin 92 will cause rocking of the arms 90, 91 whereby to reciprocate the wrapper folders 59 and 60.

The operation of my improvements may be described as follows: Magazines 3 will be charged with articles 4, and magazine 40 will be charged with wrappers 33, and, considering the parts at rest, the pusher 7 will be withdrawn from magazine 3, the feeding roller 48 will be in an inactive position, plunger 12 will be withdrawn from the chute (see Fig. 1), and the folders 57, 58, 59, 60 will be spread apart substantially as shown in Fig. 13. With an article 4 at the retainer or delivery end of the chute opposing a wrapper 33 in receiver 32, and the machine being started, the plunger 12 will advance and will push the article 4 from said retainer, whereupon the guides 34 will be swung into receiver 33 (Fig. 9), opposing such wrapper. Continued movement of the plunger will cause the wrapper and the article behind it to be pushed through opening 32^a of the receiver into passage 55, whereupon the top, bottom and end portions of the wrapper will be folded relatively to article 4, the folders 102 first causing the end portions of the wrapper to be folded against the ends of the article, as in Fig. 22. As the plunger continues to push the article and wrapper the flaps 33^a, 33^b will engage the folders 103, 104 to turn said flaps relatively to the ends of the article 4 (Fig. 24), and the plunger will then continue to push the partially wrapped article into the reduced portion 55^a of the passage until the plunger reaches the limit of its stroke to

leave the partially wrapped article in said passage, as in the position indicated in dotted lines in Fig. 14, when the plunger recedes. During the aforesaid forward movement of plunger 12, and before it reaches the limit of its stroke, the projection 52 will operate lever 10 to cause the pusher 7 to advance to push the lowermost article 4 of the stack from magazine 3 for deposit in chute 6, the guard 31 then preventing an article in chute 6 from reaching the delivery end of the chute. Upon the aforesaid return stroke of the plunger, the projection 101 will encounter the arm 97 to operate the latter toward the right in Fig. 5, whereupon the arm 94 will cause arms 90 and 91 to move, whereby the arms 84, 85 will be moved toward each other to push the folders 59, 60 toward the wrapper, (Fig. 25), and to fold the end portions 33^a, 33^b of the wrapper over the rear side of article 4. The operations of folders 59, 60 upon said portions of the wrapper are diagrammatically illustrated in Figs. 25 and 26, the lower and upper portions 33^a, 33^b of the wrapper then being yet unfolded. During continued return movement of the plunger the projection 101 will pass from the arm 97 and spring 98 will cause restoration of said arm to normal, whereupon the arm 94 will cause arms 84 and 85 to be moved outwardly to withdraw the folders 59 and 60 from the folded parts 33^a, 33^b of the wrapper. During such return movement of the plunger the feeding roller 48 will engage the lowermost wrapper 33 and 100 will feed the same into receiver 32 to be in position opposing an article 4, which will be released by the plunger when it moves finally out of the delivery end of chute 6, whereupon such article will slide into position 105 opposite the plunger ready to be pushed, on the next forward stroke of the plunger, against the aforesaid wrapper in the receiver 32, in manner before described. Upon such forward stroke of the plunger it will cause the guides 34 to be swung again into receiver 33, and will push said article 4 against the wrapper in the receiver, also pushing the wrapper with the article from the receiver to passage 55, causing such 115 wrapper to be folded in manner before described and as illustrated in Fig. 24. During such forward stroke of the plunger, and before the limit of said stroke, the dogs 77, 78 will operate the arms 71, 72 to cause the folders 57, 58 to approach for folding portions 33^a, 33^b of the previously partially folded wrapper, and since the folder 57 moves in advance of the folder 58 the folder 57 will fold the projecting portion 33^a of 120 said wrapper against the corresponding side of article 4 (Fig. 29), also causing the then partially folded lower projecting portions 33^a, 33^b of said wrapper to be folded with the portion 33^a from the positions shown in 130

Fig. 26 to the position shown in Fig. 28, and the folder 58 will operate to fold the remaining projecting portion 33^b together with the remaining partially folded projecting portions 33^c, 33^d of said wrapper over the then previously folded portions, from the position illustrated in Fig. 26 to the position illustrated in Fig. 29, leaving the wrapped article or package in such position in the 10 passage. As the plunger continues on such forward stroke, the dogs 77, 78 will pass from the arms 71, 72 whereupon the latter will snap back to the normal position and cause spreading of the folders 57, 58 15 from the wrapper, and when the plunger approaches the limit of its stroke it will push the wrapper, which is then being advanced to wrapper folding position, against the said wrapped article or package, and 20 will push the wrapped article from the wrapper folding position leaving the succeeding partly wrapped article in its place. Upon the next recession of the plunger the projection 101 will again encounter arm 97 25 to cause operation of the folders 59, 60 to fold the portions 33^c, 33^d of the last deposited wrapper, as before described, and so on.

It will be understood that each time that 30 plunger 12 returns from the wrapper folding position (Fig. 14) the plunger leaves an article in such position, the side portions 33^a, 33^b of which wrapper are folded by folders 59, 60, during such return stroke 35 of the plunger, and that during each time that the plunger advances and pushes an article in a wrapper, the portions 33^a, 33^b of the said previously deposited wrapper are folded by the folders 57, 58, completing the package; also, that each time 40 the plunger reaches the wrapper folding position, such last named package is pushed out of wrapper folding position, another wrapper and article being left in the wrapper 45 folding position upon the succeeding return stroke of the plunger. The folders 57, 58 retreat from the folding position before each succeeding wrapper and article reach such position. The several packages are 50 pushed successively from passage 55 into guide 100, by succeeding forward strokes of the plunger, and such packages may be removed from the guideway in any suitable manner, it being observed that as a result 55 of each to and fro movement of the plunger a complete package is produced and delivered.

Having now described my invention what I claim is:—

1. The combination of means to retain wrappers, means to supply and retain articles opposing the wrappers, a plunger at one side and a receiving passage at the other side of the retained wrappers and articles, 65 means to reciprocate the plunger to push

articles and wrappers therewith into the passage for partially folding wrappers on the articles, stationary folders within the passage to partially fold the wrappers upon the articles as they are pushed by the plunger along the passage one after another, a pair of opposing folders movable transversely of said passage and spaced from the stationary folders on the side away from the plunger, another pair of opposing folders 70 at an angle to the first named pair of folders and movable transversely of said passage, and means to move said pairs of folders separately and relatively to the movements of the plunger unfolded by the 75 stationary folders.

2. The combination of means to retain wrappers, means to supply and retain articles opposing the wrappers, a plunger at one side and a receiving passage at the other 80 side of the retained wrappers and articles, means to reciprocate the plunger to push articles and wrappers therewith into the passage for partially folding wrappers on the articles, a pair of opposing folders movable transversely of said passage, another 85 pair of opposing folders at an angle to the first named pair of folders and movable transversely of said passage, means to move one pair of folders toward and from projecting portions of the wrapper while the plunger moves in one direction, and means to move the other pair of folders toward and from projecting portions of the wrapper 90 while the plunger moves in another direction.

3. The combination of a wrapper receiver having opposed openings, a retainer for articles opposing said receiver, a plunger to move articles from said retainer into said 105 receiver to push wrappers therefrom with the articles, a receiving passage for said wrappers and articles, wrapper folders guided to move transversely of said passage, arms operatively connected with said folders to reciprocate them, an arm operatively 110 connected with said first named arms to move them together to cause said folders to traverse said passage, an arm connected with the last named arm, and a projection 115 operatively connected with said plunger for actuating the last named arm to cause operation of said folders upon movement of said plunger in one direction.

4. The combination of a wrapper receiver 120 having opposed openings, a retainer for articles opposing said receiver, a plunger to move articles from said retainer into said receiver to push wrappers therefrom with the articles, a receiving passage for said 125 wrappers and articles, wrapper folders guided to move transversely of said passage, arms operatively connected with said folders to reciprocate them, dogs operatively connected with said plunger to reciprocate 130

therewith to actuate said arms when moved in one direction; wrapper folders guided to move transversely to said passage relatively to the first named folders, arms operatively connected with the second named folders to reciprocate them, means operatively connecting said second named arms for conjoint operation, and a projection connected with said plunger for operating the last

named means when the plunger moves in another direction to cause operation of said folders.

Signed at New York city, in the county of New York and State of New York, this 11th day of June, A. D. 1917.

ERNEST D. ANDERSON.
